UNITED STATES PATENT OFFICE

ERNST F. MULLER, OF COLUMBUS, OHIO, ASSIGNOR TO THE JEFFERY MANUFACTURING COMPANY, OF COLUMBUS, OHIO, A CORPORATION OF OHIO

MINE CONVEYER

Application filed May 14, 1931. Serial No. 537,393.

The present invention relates to transportable conveyers of a type particularly adapted for use in coal mines, although many other applications are possible.

According to the embodiment of the invention to be hereinafter described, the conveyer is supported on a movable base, preferably in the form of a wheeled truck adapted for movement over the tracks of a mine, through the intermediary of a horizontally extending arm supported at one end on the base for pivotal movement about a vertical axis and also for vertical adjustment, and at its other end supporting the conveyer for movement relative thereto about both horizontal and vertical axes. A counterweight is provided in connection with the conveyer supporting arm and means are provided through the operation of which the conveyer may be adjusted about its horizontal supporting axis. Normally, the delivery end of the conveyer extends in overlying relation with the supporting arm and in order that this end may rest in close proximity to the arm, the driving devices for the conveyer are mounted beneath its receiving end.

While the conveyer has a general field of usefulness as a mine conveyer, it is particularly useful under certain circumstances in connection with a primary conveyer as will be hereinafter described.

In the accompanying drawings,

Figure 1 is a plan view of a practical illustrative embodiment of the invention;

Figure 2 is a side elevation of the structure shown in Figure 1;

Figure 3 is a view in vertical section of means for supporting the conveyer supporting arm on the truck;

Figure 4 is a view partly in vertical section of the connecting means between the supporting arm and the conveyer;

Figure 5 is a section on line 5-5 of Figure 2; and

Figure 6 is a view in plan showing the apparatus of the present invention as included in a loading out system in a mine.

Referring to the drawings, reference numerals 10 and 11 denote the side sills of a truck frame supported on axles 12 and 13

provided at their ends with wheels 14 and 15 adapted for engagement with the rails of a mine track, one rail being shown at 16, Figure 2. The sills 10 and 11 are connected by cross sills 17 and 18 between which and centrally of the side sills is supported a yoke 19 depending from a frame 20 which is bolted to the sills 17 and 18 by means of bolts 21.

Rigidly supported in yoke 19 in vertically projecting relation is a screw pedestal 22 which is surrounded by a tubular member 23 having internal threads engaging the threads of the pedestal. At its lower end tubular member 23 is radially expanded to form an annular ledge 24 upon which is stepped, through the intermediary of a ball bearing 25, a barrel 26. Immediately above the barrel is keyed a hub 27 from which radiate a number of levers 28 constituting a spider, through manipulation of which tubular member 23 is rotatable for vertical displacement relative to pedestal 22. Hub 27 is restrained against upward displacement by means of a cap plate 29 fixed to the upper end of tubular member 23 and in turn prevents upward displacement of barrel 26 relative to the tubular member. Upward movement of the tubular member relative to the pedestal is limited by a plate 30 secured to the top of the pedestal.

Barrel 26 has, as here shown, a horizontally extending arm 31 integral therewith. At its free end arm 31 has a vertical bearing 32 in which is journaled a neck 33 which projects downwardly from a horizontally extending bracket 34, with which, as here shown, it is integral. The bracket has an annular shoulder portion 35 stepped on a bearing surface 36 marginal to the upper end of the bearing opening. An annular plate 37 secured to the lower extremity of neck 33 engages beneath an annular shoulder formed in bearing 32 to prevent upward displacement of the neck. The neck 33 is tubular and has threaded therein a screw 38 to the lower projecting end of which is fixed a hand wheel 39.

At its free end, bracket 34 has a transverse upstanding rib 40 provided with a horizontal bore in which is disposed a pivot pin 41 whose axial line is substantially perpendicular to a

line radial to the neck 33. The under side of the bracket is provided with a plurality of apertures 42 formed about a common center and selectively engageable by means of a spring pressed pin 43 mounted in the extremity of arm 31 so that the bracket may be locked in forwardly extending alignment with arm 31 or in various angular positions relative to the arm.

10 Referring particularly to Figures 1, 2, and 5, reference numeral 44 designates generally an elongated conveyor comprising a frame made up of side walls 45 and 46 which support between them a pan 47 over which travels the working run of a conveyor belt 48, which, at the ends of the conveyor, passes about rollers 49 and 50, the former being at the delivery end and the latter at the receiving end of the conveyor. Inwardly of rollers 20 49 and 50, the idle run of the belt is engaged by rollers 51 and 52, the latter being shown in cross section in Figure 5, as exemplifying suitable structure and mounting means for all of the rollers involved in the conveyor structure. Inwardly of roller 52, the belt is 25 looped about rollers 53 and 54, the former being a drive roller which is rotated from a suitable motor 55 through an armature pinion 56, a gear 57, a sprocket wheel 58, a sprocket 30 chain 59, and a sprocket wheel 60, all of these driving devices being supported adjacent and beneath the receiving end of the conveyor. Roller 49 is provided with well known adjusting means 61 whereby the belt may be 35 suitably tensioned.

The upper edges 62 and 63 of pan 47 are outwardly flared and have secured thereto rigid guide strips 64 and 65 from whose lower edges depend flexible strips 66 and 67 in 40 contact with the upper run of the belt whereby material is kept from working under the belt edges.

It will be understood that while I have described a belt conveyor as being well suited 45 to the purposes of the invention, any suitable form of draft and material engaging devices may be used.

Somewhat forward of its medial portion but inwardly of the above described driving 50 devices, the frame members 45 and 46 have brackets 68 and 68', Figures 1 and 4, secured thereto, these brackets being provided with aligned apertures in which is engaged the pivot pin 41. To the rear of pin 41 and immediately above screw 38, a bolster 69 is 55 bolted across the frame member.

The transporting position of the conveyor is that particularly shown in Figure 2, wherein its delivery portion overlies arm 31 in substantially parallel relation thereto, bolster 69 resting on bracket 34 and a further rearward portion of the conveyor, through a transverse bottom plate, resting on cap plate 29, tubular member 23 being in its lowermost 60 position. It will be evident that arm 31 and

conveyer 44 may be swung to any desired angle relative to tubular member 23 when the conveyor is to be set in working position and the arm and conveyor may be translationally adjusted through rotation of tubular member 23 relative to the screw pedestal 22 through manipulation of the spider. Further, bracket 34 and the conveyor may be swung relative to the arm if desired upon releasing locking pin 43. Also by rotation of screw 38 through hand wheel 39, the upper end of the screw abutting bolster 69 will cause angular adjustment of the conveyor about the horizontal axis of the pin 41. It will be understood that the delivery end of the conveyor somewhat overbalances the receiving end thereof so that bolster 69 is normally in contact with the top of bracket 34 or with the upper end of screw 38 after the latter is adjusted to project above the bracket.

In order to stabilize the apparatus, an arm 70 is fixed to barrel 26 in oppositely extending relation to arm 31 and supports a suitable counterweight 71.

According to Figure 6, a room A is being developed off of the entry B, the mine track C being curved off to the room and being shown as supporting loading apparatus comprising a gathering section D articulated to a discharge section E which is mounted on a truck F. With the machine D, E, F in the position shown, it will be seen that the discharge conveyor E would be unable to discharge properly into a car G situated on the track. Under these circumstances, the conveyor 44 of the present invention may be positioned intermediate the discharge conveyor E and the car G and so adjusted as to transfer material from the conveyor to the car under all conditions. As here shown, the supporting arm 31 is angularly adjusted relative to its supporting truck and bracket 34 is angularly adjusted relative to the arm. Suitable vertical adjustment and inclination of the conveyor is, of course, obtained in the manner already described. Many other situations presenting like difficulties in properly spotting the car arise and can be most conveniently met by the apparatus of the present invention. If desired, the delivery end of the conveyor may be maintained over a car on the track and the receiving end swung from side to side of the room.

In Figure 6, the conveyor is shown in dotted lines as assuming a position for gobbing refuse over to the rib, and can, of course, be moved across to a similar position on the other side of the track. Various other maneuvers for meeting particular situations will occur to those skilled in the art, and while one of the uses of the apparatus of the present invention is as an adjunct or intermediary between a main conveyor line and a mine car, it may, of course, be used entirely independ-

ently of such apparatus and in such use provides a wide range of useful adjustment. The construction of the machine is simple and comparatively light so that whether mounted upon a truck, caterpillar tractor, slide shoe, or other support, it is capable of being shifted without difficulty to its needed position.

While I have described in detail a practical embodiment of the invention, it is to be understood that I do not limit myself as to structure except as in the following claims.

I claim:

1. Apparatus of the class described comprising a movable base, a horizontally extending arm supported on the base, a pivotal connection between the arm and base to permit the arm to swing above the base and through an unrestricted range about a vertical axis, an elongated conveyer, a pivotal connection between the arm and conveyer remote from the first named connection to permit the conveyer to swing relative to the arm about a vertical axis, a second arm in rigid connection with the first and projecting in the opposite direction therefrom, and a counterweight mounted on the second arm remote from the first mentioned pivotal connection.

2. Apparatus of the class described comprising a movable base, an upright screw pedestal supported on said base, a tubular member surrounding said pedestal and provided with internal threads operatively engaging those of the pedestal, a barrel surrounding said tubular member and stepped on a radial flange of the latter for rotation relative thereto, a horizontally extending arm rigid with said barrel, an elongated conveyer supported on said arm remote from said pedestal, and means operable to rotate said tubular member to effect its vertical displacement relative to the pedestal.

3. Apparatus of the class described comprising a movable base, an upright screw pedestal supported on said base, a tubular member surrounding said pedestal and provided with internal threads operatively engaging those of the pedestal, a barrel surrounding said tubular member and stepped on a radial flange of the latter for rotation relative thereto, a horizontally extending arm rigid with said barrel, and an elongated conveyer supported on said arm remote from said pedestal, a second arm secured to said barrel and extending in the opposite direction from the first, a counterweight supported on said arm remote from the pedestal, and means operable to rotate said tubular member to effect its vertical displacement relative to the pedestal.

4. Apparatus of the class described comprising a movable base, an upright screw pedestal supported on said base, a tubular member surrounding said pedestal and provided with internal threads operatively engaging those of the pedestal, a barrel sur-

rounding said tubular member and stepped on a radial flange of the latter for rotation relative thereto, a horizontally extending arm rigid with said barrel, an elongated conveyer supported on said arm remote from said pedestal, and a lever fixed to said tubular member above said barrel for rotating the former relative to the pedestal, the lever having a hub portion preventing upward displacement of the barrel relative to the tubular member.

5. Apparatus of the class described comprising a movable base, a horizontally extending arm supported on the base, a pivotal connection between the arm and base to permit the arm to swing above the base and through an unrestricted range about a vertical axis, an elongated conveyer supported at its medial portion on and above said arm remote from said pivotal connection for pivotal movement relative to the arm about both vertical and horizontal axes, one end of the conveyer overbalancing the other about said horizontal axis, and means engaging under the overbalancing conveyer portion and vertically adjustable to swing the conveyer about said horizontal axis.

6. Apparatus of the class described comprising a movable base, a horizontally extending arm supported on the base, a pivotal connection between the arm and base to permit the arm to swing above the base and through an unrestricted range about a vertical axis, an elongated conveyer supported at its medial portion on and above said arm remote from said pivotal connection for pivotal movement relative to the arm about both vertical and horizontal axes, one end of the conveyer overbalancing the other about said horizontal axis, a vertical screw engaging the overbalancing conveyer portion, and means operable to rotate and vertically displace the screw to adjust the conveyer about said horizontal axis.

7. In apparatus of the class described, an elongated conveyer, and mounting means for the conveyer, said means comprising a horizontally extending member, a horizontal bracket having a tubular neck portion journaled in said member, an elongated conveyer extending above said bracket, a pivotal connection between the conveyer and bracket remote from said neck, said connection having a horizontal pivoting axis substantially perpendicular to a line radial to the neck, one end of the conveyer overbalancing the other about said horizontal axis, a screw threaded in said tubular neck and rotatable for vertical adjustment relative thereto, the overbalancing portion of said conveyer being supportable on said screw for adjustment thereby about said horizontal axis, and means operable to rotate said screw.

8. Apparatus of the class described comprising a wheeled truck, an arm pivotally

supported by the truck for swinging movements thereabove on an upright axis, an elongated conveyer frame pivotally supported on the outer end of said arm for swinging movements relative to the arm about horizontal and upright axes, one end of said frame overbalancing the other about said horizontal axis, said arm and conveyer frame in the normal transporting position of the parts extending in the longitudinal direction of the truck with the overbalancing end of said frame above the truck, and means for supporting said overbalancing end.

9. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes of which the upright axis is normally nearer the swinging axis of the arm than the horizontal axis, one end of said frame overbalancing the other about said horizontal axis, said arm and conveyer frame in the normal transporting position of the parts extending in the longitudinal direction of the truck with the overbalancing end of said frame above the truck, and means for supporting said overbalancing end.

10. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes, one end of said frame overbalancing the other about said horizontal axis, said arm and conveyer frame in the normal transporting position of the parts extending in the longitudinal direction of the truck with the overbalancing end of said frame above the truck, means for supporting said overbalancing end, a second arm in connection with the first and extending in the opposite direction from the first, and a counterweight carried by said second arm remote from said last-named axis.

11. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes, one end of said frame overbalancing the other about said horizontal axis, said arm and conveyer frame in the normal transporting position of the parts extending in the longitudinal direction of the truck with the overbalancing end of said frame above the truck, means for supporting said overbalancing end, and means operable to adjust said arm vertically relative to the truck.

12. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes, one end of said frame overbalancing the other about said horizontal axis, said arm and conveyer frame in the normal transporting position of the parts extending in the longitudinal direction of the truck with the overbalancing end of said frame above the truck, means for supporting said overbalancing end, and means operable to adjust said arm vertically relative to the truck.

13. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes, one end of said frame overbalancing the other about said horizontal axis, said arm and conveyer frame in the normal transporting position of the parts extending in the longitudinal direction of the truck with the overbalancing end of said frame above the truck, means for supporting said overbalancing end, said last-named means including an upright screw carried by said arm and adjustable to tilt said frame about its horizontal axis.

14. Apparatus of the class described comprising a wheeled truck, an arm pivotally supported by the truck for swinging movements thereabove on an upright axis, an elongated conveyer frame pivotally supported on the outer end of said arm for swinging movements relative to the arm about horizontal and upright axes, of which the upright axis is normally nearer the swinging axis of the arm than the horizontal axis, one end of said frame overbalancing the other about said horizontal axis, said arm and conveyer frame in the normal transporting position of the parts extending in the longitudinal direction of the truck with the overbalancing end of said frame above the truck, and means for supporting said overbalancing end, said last-named means including a screw coaxial with the upright pivoting axis of the frame and adjustable to tilt the frame about its horizontal axis.

ERNST F. MULLER.
